[57] CLAIM

The ornamental design for an automobile, as shown and described.

DESCRIPTION

FIG. 1 is a front perspective view of an automobile constructed in accordance to the teachings of the present design;

FIG. 2 is a side view of the automobile shown in FIG. 1, it being understood that the side opposite the side shown is a mirror image thereof;

FIG. 3 is a front view of the automobile shown in FIG. 1; and,

FIG. 4 is a rear view of the automobile shown in FIG. 1.

The top or roof of the automobile is understood to be plain and unornamented.
